(57) **CLAIM**

We claim the ornamental design for an outside rearview assembly with turn signal, as shown and described.

DESCRIPTION

FIG. 1 is a top perspective view of an outside rearview assembly with turn signal of the present disclosure;

FIG. 2 is a bottom perspective view of the outside rearview assembly with turn signal of FIG. 1;

FIG. 3 is a first side perspective view of the outside rearview assembly with turn signal of FIG. 1;

FIG. 4 is a second side perspective view of the outside rearview assembly with turn signal of FIG. 1;

FIG. 5 is a rear elevational view of the outside rearview assembly with turn signal of FIG. 1;

FIG. 6 is a front elevational view of the outside rearview assembly with turn signal of FIG. 1;

FIG. 7 is a top plan view of the outside rearview assembly with turn signal of FIG. 1; and,

FIG. 8 is a bottom plan view of the outside rearview assembly with turn signal of FIG. 1.

In the drawings, the broken lines depict portions of the article that form no part of the claimed design.
